UNITED STATES PATENT OFFICE.

FREDERICK VAN PATTEN, OF AUBURN, NEW YORK, ASSIGNOR TO DRIGGS,
MOSHER & CO., OF SAME PLACE.

DEVICE FOR MAKING BUTTON-MAKING MOLDS.

SPECIFICATION forming part of Letters Patent No. 257,537, dated May 9, 1882.

Application filed August 18, 1880. (No model.)

To all whom it may concern:

Be it known that I, FREDERICK VAN PATTEN, of Auburn, in the county of Cayuga and State of New York, have invented certain new and useful Improvements in Molds for Making Buttons of Plastic Material, of which the following is a specification.

My invention relates mainly to metal molds or dies adapted for use in pairs, and between 10 which a series of small sheets or a large sheet of plastic material is placed, compressed, and cut in circular pieces representing buttons.

Heretofore it has been considered a slow and expensive operation to prepare a pair of these dies on account of the extreme care necessary 15 to have the circular edge of each matrix forming the back of a button (on a plate containing perhaps a hundred of them) coincide exactly with the circular edge of each matrix forming 20 the front of a button in the second plate of the pair, to avoid the formation of any fins upon the circular edge of the buttons.

The object of my invention is to produce 25 molds for making buttons of plastic material, in which the edges of each pair of matrices in said molds will exactly coincide, and the location and direction of the perforations in said buttons will be the same in each one of a series, and to produce these molds at a much reduced 30 cost.

My invention consists in combining with dies 35 constructed to mold the front or back of buttons a perforated templet adapted to fit over each single-button matrix, a flat rod secured to the back of said templet, and a mortised support and guide adapted to slide upon said flat rod and rest upon and against the edge of the die-plate.

In the accompanying drawings, Figure 1 40 represents in perspective the top and bottom die-plates of a mold used in forming a few buttons at a time. Fig. 2 represents in plan the under side of a portion of the die used in forming the front of buttons. Fig. 3 represents the 45 two dies of a button-mold in vertical section. Fig. 4 represents in perspective the transfer or guide plate resting upon the die-plate provided for forming the back of buttons. Fig. 5 represents the same in vertical section. Fig. 6 represents in plan a portion of the bottom die-plate. Fig. 7 represents in perspective the templet,

its guide, and support. Fig. 8 represents the same in vertical section and resting upon the bottom die-plate, the latter being also in section. Fig. 9 represents in transverse section one of 55 the buttons formed with my improved molds.

In the drawings, A represents the die-plate used to mold the top of buttons, and B the die-plate for the bottom of buttons, each plate being provided with suitable cavities or matrices 60 having the required form for that purpose. To have the edge of these matrices made to coincide exactly when brought face to face, I provide a transfer-plate, C, generally of the same size as regards its surface as the plates A and B. This transfer-plate is provided with a series of regularly spaced holes, c, extending therethrough, having a diameter equal to or larger than the button intended to be produced. It has also two or more holes, d, extending 70 through it to receive dowel-pins d', made to enter therein from either side of the plate. When the transfer-plate is thus completed it is placed upon and clamped to the plate B, and corresponding dowel-pin holes are drilled through 75 the latter plate. The same operation is repeated in regard to the plate A after reversing the plate C upon its face; or the three plates may first be clamped firmly together, with the face of plate A toward the face of B and with the 80 transfer-plate C between them, and the required number of dowel-pin holes d drilled through the three plates at one operation. Dowel-pins are then prepared to fit the holes d, and having the transfer-plate or drill-guide C secured there- 85 with upon, for example, the bottom die-plate, B, as shown in Figs. 4 and 5, a suitably sized and shaped drill is passed through each hole c as a guide, and each shallow saucer-like matrix for the bottom of the buttons may thus be 90 drilled in succession. Cavities b' are also made between the matrices to receive any surplus of the plastic material. To complete these matrices they require two short pins, e, to project into the plastic material of buttons, and form, ac- 95 cording to their length, two perforations, either incomplete or complete, for the passage of the thread that is to secure the button to a garment. It is important that these pins should be at equal distance from the center of each matrix, 100 and as they are secured to the die-plate by drilling the latter, I use, to secure uniformity in the

latter, a peculiarly-constructed templet, F, having its central portion convex to correspond with the concavity of each matrix, with a projecting circular edge to overlap and fit the edge 5 of said matrix. This templet is secured to a flat guide-rod, F', fitting in a mortise of the guide or support F², the mortise being of such size as to allow the rod to slide therein, so that the templet can cover any one of the matrices 10 in the die-plate while the guide F² or the edge of its groove f², remains upon the edge of said plate. The parts F' and F² may also be united by means of a binding thumb-screw entering the top or bottom of the guide F² and pressing 15 upon the rod F'. The templet F has two perforations, f, to guide the cutting end of the drill used to perforate the bottom of each of the matrices, after which the pins e are driven and secured in the perforations thus made. The 20 upper die-plate is completed in a manner analogous to the lower one. The upper plate being placed face upward, the same transfer-plate C is reversed and placed upon it and retained thereon by dowel-pins, its perforations c being 25 used to guide a suitably-shaped drill, (the shape varying according to the predetermined form to be given to the face of buttons.) After each upper matrix has been drilled and polished a templet nearly similar to the templet F, but 30 corresponding with the shape of the cavity, and having only one hole, f, in the center, is used to guide the end of a drill used to bore a hole in the center of said cavity for the purpose of

receiving a pin, a. This pin is to form in the top of the button a recess sufficient to receive 35 the thread used to secure the buttons. Its top is generally even with the face of the die-plate A, so that when the plastic material is pressed and indented between the die-plates the end of the pin a on one side and the ends of the 40 pins e on the other side will be about in the same plane and nearly touch. I prefer to have the two holes e' in the button completed by 45 drilling the very small amount of material in the center thereof to produce even holes with smooth edges; but they may be otherwise produced at once by making the pins e long enough to slightly project above the face of the mold B, as shown at e², Fig. 1. They will then extend for a short distance alongside of the pin 50 a and produce perforations extending through the buttons. I have shown only two pins, e, for each matrix; but in some cases four of them may be used.

Having now fully described my invention, I 55 claim—

The templet F, in combination with its rod F', secured to the back of the templet, and the mortised support and guide F², adapted to slide upon said rod and against the edge of a 60 rectangular plate, substantially as and for the purpose described.

FREDERICK VAN PATTEN.
